US00D883967S

(12) **United States Design Patent** (10) **Patent No.:** **US D883,967 S**
(45) **Date of Patent:** **** May 12, 2020**

(54) **EXTENSION MODULE**

(71) Applicant: **Wistron NeWeb Corp.**, Hsinchu (TW)

(72) Inventors: **Bau-Yi Huang**, Hsinchu (TW);
Chin-Wei Chen, Hsinchu (TW)

(73) Assignee: **WISTRON NEWBEC CORP.**, Hsinchu (TW)

(**) Term: **15 Years**

(21) Appl. No.: **29/677,249**

(22) Filed: **Jan. 18, 2019**

(51) LOC (12) Cl. **14-03**

(52) U.S. Cl.

USPC **D14/240**; D14/358

(58) **Field of Classification Search**

USPC ... (57) **CLAIM**

The ornamental design for an extension module, as shown and described.

DESCRIPTION

FIG. 1 is a front perspective view of an extension module in accordance with our new design;

FIG. 2 is a rear perspective view thereof;

FIG. 3 is a front view thereof;

FIG. 4 is a rear view thereof;

FIG. 5 is a left view thereof;

FIG. 6 is a right view thereof;

FIG. 7 is a top plan view thereof;

FIG. 8 is a bottom plan view thereof;

FIG. 9 is another front perspective view showing the extension module of FIG. 1 in a position of use assembled with a wireless signal transmission device;

FIG. 10 is a rear perspective view thereof;

FIG. 11 is a front view thereof;

FIG. 12 is a rear view thereof;

FIG. 13 is a left view thereof;

FIG. 14 is a right view thereof;

FIG. 15 is a top view thereof; and,

FIG. 16 is a bottom view thereof.

The additional broken line subject matter showing the wireless signal transmission device in FIGS. 9-16 depict environment only and form no part of the claim, while all other broken lines depict portions of the extension module that form no part of the claimed design.

1 Claim, 16 Drawing Sheets
